Primary Examiner — Kelley Donnelly(74) *Attorney, Agent, or Firm* — Tarter Krinsky & Drogin LLP**CLAIM**

The ornamental design for a product display assembly, as shown and described.

DESCRIPTION

FIG. 1 is a front perspective view of a product display assembly;

FIG. 2 is a front view thereof; and,

FIG. 3 is a blown up view of the circled portion of the shelf marked in FIG. 2.

The broken lines illustrate unclaimed portions and form no part of the claimed design.
